UNITED STATES PATENT OFFICE.

SAMUEL GEORGE TATE, OF CHICAGO, ILLINOIS, ASSIGNOR TO UNION SPECIAL MACHINE COMPANY, OF CHICAGO, ILLINOIS, A CORPORATION OF ILLINOIS.

SEAM FOR SEWED ARTICLES.

1,271,240.

Specification of Letters Patent.

Patented July 2, 1918.

Application filed July 23, 1917. Serial No. 182,262.

To all whom it may concern:

Be it known that I, SAMUEL GEORGE TATE, a citizen of the United States, residing at Chicago, in the county of Cook, State of Illinois, have invented certain new and useful Improvements in Seams for Sewed Articles, of which the following is a description, reference being had to the accompanying drawing, and to the figures of reference 10 marked thereon.

The invention relates to new and useful improvements in seams for sewed articles, and more particularly to a covering seam or seam which may be used for uniting and 15 covering the meeting edges of two sections of fabric.

An object of the invention is to provide a seam having a plurality of rows of connected lines of stitching wherein one of the 20 rows of stitching includes thread loops which are locked against raveling, which line of stitching also serves to lock the loops in the other line or lines of stitching against raveling.

25 A further object of the invention is to provide a seam of the above character wherein in the edges of the fabric sections are abutted, the needle loops of one of the rows of stitching passing downwardly between the abutted edges, and wherein the needle thread of said row is supported by a covering thread passing twice across the abutted edges between each pair of needle thread loops in said thread.

30 These and other objects will in part be obvious, and will in part be hereinafter more fully disclosed.

In the drawings,—

Figure 1 is a top plan view on an enlarged scale, showing two fabric sections 40 united by my improved seam;

Fig. 2 is a bottom plan view of the same;

Fig. 3 is a top plan view, but showing a slightly modified form of the invention;

Fig. 4 is a bottom plan view of the same shown in Fig. 3;

Fig. 5 is a top plan view similar to Fig. 1, but showing a slightly modified form of the invention; and

Fig. 6 is a bottom plan view of the seam shown in Fig. 5.

The invention consists in a seam for joining fabric sections preferably having their meeting edges abutted or very slightly over-

lapped. Parallel rows of needle thread 55 loops pass respectively downwardly through the fabric sections adjacent the meeting edges thereof. A looper thread is looped through the needle thread loops in one of the rows, and this looper thread is extended laterally across the meeting edges and secured by the needle thread loops in another row, while the needle thread loops in this last named row are locked by the looper thread loops which pass through the needle thread 60 loops and are secured by the next formed needle thread loops in the same row.

Referring more in detail to the drawings, the seam shown in Figs. 1 and 2 is a three-needle seam in which the needles operate to 70 produce three parallel rows of needle-thread loops. The three needle threads are indicated at 1, 2 and 3 respectively. The needle loops of these needle threads are also indicated respectively at 4, 5 and 6. The fabric 75 sections are indicated at F and F'. The meeting edges of the fabric sections are indicated at f. The needle threads 1 and 3 are formed into parallel rows of loops which extend respectively downwardly through the 80 fabric sections F and F' adjacent the meeting edges thereof. A needle thread 2 is formed into a row of loops which pass downwardly between the abutted edges of the fabric sections. A covering thread 7 is 85 passed around each needle loop in the outer rows and twice underneath the needle thread in the center row between each adjacent pair of needle thread loops 5.

This covering thread forms a support for 90 the center needle thread, the loops of which do not penetrate the fabric sections, but which pass between the abutted edges of the fabric sections. Inasmuch as the covering thread passes twice across the abutted edges 95 and in spaced relation to each other, the needle thread 2 is thereby given a two-point support by this covering thread between adjacent needle thread loops of the needle thread 5.

The needle thread loops on the lower surface of the fabric are secured by two looper threads. One of the looper threads is carried by a looper moving transversely of the line of feed and entering the needle thread loops of two of the rows, that is, the needle thread loops 5 and 6. The other looper thread is carried by a single looper and locks 100 105

not only the first mentioned looper but forms with the third row of needle thread loops, (that is, the needle thread loops 4) the ordinary two-thread double locked stitch.

- 5 The loops in the first mentioned looper thread, which are indicated at 8 in the drawings, are entered by the needle thread loops 4 and thus the locking of the needle thread loops 4 by the looper thread 9 brings about 10 a locking of the loops 8 and consequently a locking of the needle loops in the other rows and thus a locking of all of the concatenated loops, resulting in the formation of a seam having stitches which will not ravel when 15 the seam is placed under strain. One strand of each loop 8 in the looper thread is also carried laterally and in the direction of the feed, so as to be entered by the next two needle thread loops 5 and 6.
- 20 It will be noted that the needle thread loops in the needle thread 1 are slightly out of line with the needle thread loops 5 and 6, as shown in the drawings. This, however, is immaterial so far as the seam *per se* is 25 concerned, the essential feature consisting in the connected rows of stitches, wherein one line of stitching includes loops which are locked against raveling, which loops in turn serve to prevent the thread loops in the other 30 rows of stitches from raveling when the fabric sections are placed under strain.

In Figs. 3 and 4 of the drawings, I have shown a slightly modified form of the invention, in that there are four rows of needle 35 thread loops indicated at 12, 13, 14 and 15. A covering thread 7 joins all four rows of needle thread loops extending around the needle thread loops in the outer rows and underneath the threads in the intermediate 40 rows. A looper thread 16 is formed into thread loops which are passed through the needle thread loops 13, 14 and 15 and secured by the needle thread loop 12. A looper thread 17 forms a two-thread double locked 45 stitch with the needle thread loops 12 in the manner described in connection with Figs. 1 and 2. Except as to the number of rows of threads and the position of the thread relative to the meeting edges, the 50 thread concatenations shown in these figures are precisely the same as that shown in Figs. 1 and 2.

In Figs. 5 and 6 I have shown a further modification of the invention which consists 55 of two rows only of needle thread loops, the needle threads being indicated at 18 and 18^a and the thread loops at 19 and 20. These rows of needle thread loops are disposed on opposite sides of the meeting edges of the fabric sections. A looper thread 21 is formed into loops 22 which pass through the needle thread loops 19. These looper thread loops are entered by the next needle loops formed in the same needle thread and the 60 looper thread loops are also extended later-

ally across the meeting edges of the fabric sections and are entered and secured by the needle thread loops in the other needle thread. A looper thread 23 is formed into a series of loops which are passed through 70 the needle thread loops 20 and these looper thread loops are secured by the same needle thread loops forming the well known two thread double locked stitch. This two thread double locked stitch will not ravel 75 and as the looper thread of the other of stitches is locked thereby any strain on the fabric sections will not cause the stitches to ravel. A covering thread 7 described in connection with Figs. 1 and 2 is used.

80 From the above it will be apparent that I have provided a seam which is preferably used in joining the abutted edges of knitted fabric sections, which seam is very strong and which very efficiently covers the ends 85 of the threads of the fabric sections. Furthermore, the stitches of my improved seam will not ravel when the fabric sections are placed under strain, as one of the lines of stitching in each instance includes locked 90 stitches and these locked stitches serve to lock the other thread loops which are concatenated either directly or indirectly therewith.

95 While I have described the invention as applied to fabric sections having their edges abutted, it is obvious that the seam from certain aspects of the invention may be used in other relations.

Having thus described my invention, 100 what I claim as new and desire to secure by Letters Patent, is:—

1. In a seam, the combination with fabric sections having meeting edges, of two parallel rows of needle thread loops respectively 105 extending downwardly through the fabric sections adjacent the meeting edges thereof, the needle thread loops of one row being staggered relative to the needle thread loops of the other row, a looper thread having loops extending through the needle thread loops in one of said rows, said looper thread loops being extended laterally across the meeting edges of the fabric sections and secured by the needle thread loops in the other 110 row and a looper thread formed into loops concatenated with said last named row of needle thread loops to form therewith locked 115 stitches.

2. In a seam, the combination with fabric 120 sections having meeting edges, of two parallel rows of needle thread loops respectively extending downwardly through the fabric sections adjacent the meeting edges thereof, the needle thread loops of one row being staggered relatively to the needle thread loops of the other row, a looper thread having loops extending through the needle thread loops in one of said rows, said looper 125 thread loops being extended laterally across 130

the meeting edges of the fabric sections and secured by the needle thread loops in the other row, and a looper thread formed into loops concatenated with said last named row 5 of needle thread loops to form therewith locked stitches, and a covering thread for connecting the needle threads on the upper face of the fabric.

3. In a seam, the combination with fabric 10 sections having their meeting edges abutted, of two parallel rows of needle thread loops respectively extending downwardly through the fabric sections adjacent the meeting edges thereof, another row of needle thread 15 loops arranged intermediate and parallel with said first mentioned rows and extending downwardly between the fabric sections, a looper thread looped through all the needle thread loops of two of said rows and around 20 the needle thread loops of the other rows, a second looper thread locking the needle thread loops of said other or remaining row and the loops of said first mentioned looper thread, and a single covering thread looped 25 around each of the needle thread loops of the first mentioned rows on the upper face of the fabric and forming a two-point support for the needle thread of the intermediate row between adjacent needle thread loops 30 thereof.

4. In a seam, the combination with fabric sections having their meeting edges abutted, parallel rows of needle thread loops, a looper thread formed in the loops which are passed 35 through the needle thread loops of all the rows but one and concatenated with the needle thread loops in the remaining row, and a looper thread having loops concatenated with the needle thread loops only in 40 said remaining row, said last mentioned looper thread and needle thread loops co-

operating to lock the first mentioned looper thread.

5. In a seam, the combination with fabric sections having their meeting edges abutted, 45 parallel rows of needle thread loops, a looper thread formed in the loops which are passed through the needle thread loops of all the rows but one and concatenated with the needle thread loops in the remaining row, 50 and a looper thread having loops concatenated with the needle thread loops only in said remaining row, said last mentioned looper thread and needle thread loops co-operating to lock the first mentioned looper 55 thread, and a covering thread connecting the outer rows of needle threads on the upper face of the fabric.

6. In a seam, the combination with fabric sections having their meeting edges abutted, 60 of two parallel rows of needle thread loops respectively extending downwardly through the fabric sections adjacent the meeting edges thereof, another row of needle thread 65 loops arranged intermediate and parallel with said first mentioned rows and extending downwardly between the fabric sections, means for securing all of said needle thread loops, and a single covering thread looped around each of the needle thread loops of 70 the first mentioned rows on the upper face of the fabric and forming a two-point support for the needle thread of the intermediate row between adjacent needle thread 75 loops thereof.

In testimony whereof, I affix my signature in the presence of two witnesses.

SAMUEL GEORGE TATE.
